UNITED STATES PATENT OFFICE.

CARL WILLIAM OTTO ERICHSON, OF HAMBURG, GERMANY.

BARREL-MAKING MACHINE.

SPECIFICATION forming part of Letters Patent No. 427,504, dated May 6, 1890.

Application filed August 30, 1889. Serial No. 322,397. (No model.)

To all whom it may concern:

Be it known that I, CARL WILLIAM OTTO ERICHSON, a subject of the King of Denmark, residing at Hamburg, in the German Empire, 5 have invented certain new and useful Improvements in Barrel-Making Machines, of which the following is a specification.

My invention relates to the manufacture of barrels or casks and the machinery or apparatus therefor; and the objects of my said invention are an improved means for feeding particularly continuous boards provided with lateral interstices into the apparatus and for automatically rolling up said board or boards, 15 so that the two ends meet one another, drawing the cask in at the chines, and placing auxiliary truss-hoops on the barrel, which then is released to drop out of the machine. I obtain these improvements by means of the 20 mechanisms illustrated in the accompanying drawings, in which—

Figure 1 is a vertical section of the entire machine on the line II II in Fig. 2, which is a top view of the entire machine, part of the 25 feeding-table being broken off to better show the device which serves for feeding the board. Fig. 3 shows a front view of the machine partly in section. Figs. 4 to 6 are a cross-section and two detailed views representing different positions of the slightly-modified feeding device. Figs. 7 and 8 are two detailed 30 views of the mechanism employed to draw in the cask at the chines and to release the finished barrel from the machine.

Similar letters refer to similar parts 35 throughout the several views.

The essential parts of the machine which I employ to carry my invention into effect are the board or stave supporting or retaining 40 disks $b' b'$, supported by the frame of the machine, guided between the standards $k' k'$, and actuated by special mechanism to slide in the frame in the direction of the axis of the barrel to be formed. The said disks $b' b'$ are 45 provided with a notch a^x for passing the staves or continuous board g' from a table g into the circular cavity of the disks, wherein the ends of the staves or the scalloped lateral edges of the board g' , forming the cask, are received 50 and guided, while they are carried around by means of a toothed intermittently-rotated yielding ring O . The said supporting or re-

taining disks $b' b'$ also serve to receive and carry one or more auxiliary truss-hoops P , which are to be placed on the cask or barrel 55 after it is drawn in at the chines. This will be effected by moving the said disks $b' b'$ toward one another, whereby the ends of the staves or the lateral edges of the board will enter into the truss-hoops P , whereby they 60 are pressed firmly on the barrel to bring the staves or the scalloped parts of the board into close contact with one another.

The yielding ring O , which consists of two or more segments o' , Fig. 1, toothed in their 65 outer periphery, is slipped over a periodically-rotated disk Y , upon which it is prevented from turning by means of a tooth or feather o , fitting to corresponding notches of either one or more of the said segments o' . These 70 segments o' are connected with one another by bolts sliding within suitable notches in order to allow a contraction of the ring O when its supporting-disk Y is withdrawn, so that the finished barrel with the yielding 75 ring O may be removed from the machine.

Instead of placing a yielding or contractible ring O over the intermittently-rotated disk Y and releasing the same on withdrawal of the disk, together with the barrel, toothed 80 sectors o^x , radiating from the center of rotation, are connected to the said disk Y . These sectors are guided by projections o^y of the disk Y extending through radial notches o^z of the sectors o^x , mounted under corresponding 85 angles, to another upon a rod o^7 , which extends through the hollow shaft Y^2 of the disk Y , and may be operated by the hand-wheel o^9 at the end of the shaft Y^2 opposite to the disk Y . The eccentrics or cams o^6 engage 90 either one with one of the sectors o^x by the aid of a notch o^8 , so that on turning the rod o^7 by the hand-wheel o^9 the sectors will be radially moved on the disk Y , as may be understood from Figs. 5 and 6 of the drawings, 95 showing both the extreme positions which the sectors may occupy in relation to the rotating disk Y .

The machine is set in motion from a pulley A , mounted upon the shaft A' , which is transversely arranged at one end of the machine, where it rests in suitable bearings A^0 . The shaft A' is provided with a friction-wheel or bevel-gear B , adapted to engage with either

one of two wheels C C', movable upon a shaft C² in front of the machine, so that a so-called "change-gear" is formed by these three wheels. By means of a treadle E, pivoted to the frame 5 of the machine, the said two wheels C and C' are caused to slide upon their shaft in such a manner that either one will mesh with the bevel-wheel B upon the aforesaid driving-shaft A', in order to transmit motion from the 10 same through a chain-gearing D D' upon the shaft Y² of the said feeding-disk Y and the contractible ring O. Upon the said driving-shaft A' is mounted a second wheel F, Fig. 2, operating another wheel G, which freely 15 turns on another shaft G', located parallel to the former shaft A', and it is adapted to be periodically coupled with a disk I, firmly mounted upon the same shaft G', and thereby to transmit motion to this shaft and to cams 20 K K' and cranks L, fixed thereon. The cams or eccentrics are directly connected by the aid of their respective rods with the said stave supporting or retaining disk and truss-hoop carrier b' located next thereto, while 25 the cranks L at the ends of the said shaft G' transmit motion by means of suitable connecting-rods L' upon the other stave-supporting disk b' in such a manner that both the stave-supporting disks are simultaneously 30 moved in their guides, either approaching to or departing from one another.

In order to periodically actuate the shaft G', carrying the actuating-cams K K' and cranks L by coupling the said loosely-turning wheel G with the firmly-mounted disk I, a bolt M M', guided in the latter, tends to enter, under the action of a spring N, into claws 35 Q, projecting from the hub of the said loose wheel G, unless it is prevented from so doing by the wedge-shaped noses S or S' engaging 40 behind a projection M of the said bolt, and thereby retaining the latter M M' from the claws of the loose wheel against the tendency of the spring N. The wedge-shaped noses S 45 S' are secured to an oscillating arm R, pivoted to the frame of the machine and actuated by a treadle H under the intermediation of the shaft H', lever H², and connecting-rod H³. If, when in the position in which the stave-supporting disks b' b', hereinafter also called 50 "truss-hoop carriers," are farthest from one another, the said bolt M M' is withdrawn from the claws of the said loose wheel G by means of the incline of one of the said wedge-shaped 55 noses S, so that its shaft G' is at rest and the treadle H is pressed down for a short time, and thereby the said arm R, carrying the said noses, is elevated, the said bolt M M' is then released from the respective nose S and will 60 be instantaneously pulled against the hub of the said loose wheel G, under the action of the spring N, and engage with the claws Q of the wheel. The latter is now arranged to turn the said disk I and the shaft G', whereon 65 it is firmly secured, until the said bolt M M' is again withdrawn from the claws of the loose wheel G by one of the said noses S S', where-

upon the shaft will be instantaneously brought to a standstill. During this short period of the motion of the said secondary shaft both 70 truss-hoop carriers b' b' are moved from their extreme position toward one another, under the co-operation of the said eccentrics K K' and crank-disks L on the shaft G', in such a manner that the inner border of the truss-hoop carriers b' b' will grasp over the ends of the staves or the scalloped sides of the board intended to form the wall or body of the barrel, thereby simultaneously pressing the inner face of the board or staves upon the periphery of the said contractible ring or disk O. On actuating a separate treadle E the disk Y, carrying the said contractible ring O, is rotated together with the latter, and thereby the board or staves rolled up and drawn 80 into the cavity of the truss-hoop carriers b' b' until a complete cylinder is formed. If the said treadle E is then released, the disk Y, with the contractible ring O, is caused to stand still, whereupon the other treadle H is 90 again operated, so that the said coupling-bolt M M' will be released from the corresponding nose S' of the said arm R and engage with the claws Q of the said loose wheel G on the said secondary shaft G'. In consequence 95 thereof the shaft G', together with the said cams K K' and crank-disks L, is again caused to rotate, and thereby advance the truss-hoop carriers b' b' a certain distance, while the scalloped sides of the board or the 100 staves are bulged and drawn in at the ends of the cask and the truss-hoops P placed firmly on the same. The truss-hoop carriers b' b' are then withdrawn by operating again the respective treadle H, that they may return to their initial position, Fig. 7, in order to release the finished barrel, together with the truss-hoops P, while the said coupling-bolt M M', by means of the respective nose S of the arm R, is withdrawn from the 105 claws Q of the said loose wheel and the said secondary shaft comes to a standstill. 110 T is a horizontally-disposed rod loosely mounted in a bearing t and rigidly connected at one end to the adjacent hoop-carrier disk b'. This rod is provided with a collar T', rigidly secured thereon. 115 V is a lever fulcrumed at v upon a stationary arm v', and with its lower end collar T' of rod T is designed to engage. 120 W is a lever fulcrumed at its lower end and secured near its upper end to shaft Y². This lever is on a line with lever V, so as to be moved rearward when said latter lever is turned on its pivot by the moving forward of rod T, when hoop-carriers b' are drawn toward each other. The upper end of lever W is handled, so as to be manipulated by hand. In consequence of the oscillation of the lever W the shaft Y², together with the disk Y, is 125 withdrawn into the position indicated by dotted lines, and thereby the yielding ring O, which is loose on said disk, is released from the latter, so that it is enabled to contract or 130

to be folded together, and to be removed, together with the finished barrel, from the machine as soon as the operator has entirely withdrawn the disk Y into the cavity of the 5 respective truss-hoop carrier b'.

Before starting the machine again for forming a new barrel new truss-hoops must of course be put into their rest within the truss-hoop carriers b' b'.

Having now particularly described the nature of my said invention and in what manner the same is to be performed, I declare that what I claim is—

1. In a barrel-making machine, the stave 15 supporting or retaining disks movable toward or away from each other, and the central yielding or contractible ring or rings, together with their movable bearing, upon which they are loosely secured, substantially as set forth.

2. In a barrel-making machine, the stave 20 supporting or retaining disks movable toward or away from each other, the actuating-cams K K', connected to one of said disks, and the crank L and rod L', connected to the other disk, 25 means for operating said cams and crank, and the central yielding or contractible ring or rings, substantially as set forth.

3. In a barrel-making machine, the stave 30 supporting or retaining disks movable toward or away from each other, the central disk having a movable shaft, and yielding or contractible ring or rings loosely secured on said disk and having outer toothed peripheries, substantially as and for the purpose set forth.

4. In a barrel-making machine, the stave 35 supporting or retaining disks movable toward

or away from each other, means for operating the same, the central disk Y, together with its movable shaft, the yielding or contractible ring or rings loosely secured on said disk, the 40 rod T, connected to one of said retaining-disks, and the lever connected to said movable shaft operated by said rod, substantially as set forth.

5. In a barrel-making machine, the combination of the stave supporting or retaining 45 disks movable toward or away from each other, the rotary shaft A', the intermittently-rotated shaft G', and the cams K K' and crank L, operated by said latter shaft, substantially as set forth.

6. In a barrel-making machine, the combination of the stave supporting or retaining disks movable toward or away from each other, the central disk, together with its shaft, the yielding or contractible ring or rings on said 55 disk, the rotary shaft A', the intermittently-rotated shaft G', the wheel G, loosely secured on said latter shaft and gearing with said former shaft, the means for engaging said wheel G with its shaft, the cams K K' and crank L, 60 operated by said latter shaft for moving said retaining-disks, and means for imparting motion to said disk Y and its shaft, substantially as set forth.

In testimony that I claim the foregoing as 65 my invention I have signed my name, in presence of two witnesses, this 2d day of July, 1889.

CARL WILLIAM OTTO ERICHSON.
